DRILLING MACHINE

Leo Robbins, New York, N. Y., assignor, by mesne assignments, to Reconstruction Finance Corporation, a corporation of the United States

Application October 12, 1942, Serial No. 461,723

14 Claims. (Cl. 125—30)

This invention relates to the art of making wire-drawing dies and in particular to the drilling of holes in diamonds used in said dies.

The general object of the present invention is to devise automatic means for drilling the holes in the diamonds.

A further object is to devise automatic means for drilling extremely fine holes.

The principles of the invention will be defined in the claims and certain embodiments intended for the purpose of illustrating these principles will be described in connection with the accompanying drawings, in which:

Fig. 1 is an end elevation of apparatus embodying the invention;

Fig. 2 is a plan view;

Fig. 3 is a front elevation;

Fig. 4 is a section on the line 4—4 of Fig. 3;

Fig. 5 is a fragmentary view partly in section showing a lever arm and mounting therefor;

Fig. 6 is an elevational view partly in section showing the drill spindle and bearings therefor, and the housing for the drill spindle and bearings;

Fig. 7 is a section on the line 7—7 of Fig. 6;

Fig. 8 is an isometric and partly diagrammatic view showing the drill, the work holder and associated elements;

Fig. 9 is an enlarged fragmentary view of certain parts of the bracket in which the work holder is mounted;

Fig. 10 is a front elevational view partly in section of a modification showing a modified form of means for actuating the work holder;

Fig. 11 is a plan view partly in section, the upper part of Fig. 11 being taken on the line 11a—11a of Fig. 10 and the lower part of Fig. 11 being taken on the line 11b—11b of Fig. 10;

Fig. 12 is a fragmentary view on the line 12—12 of Fig. 11;

Fig. 13 is a front elevational view showing a microscope mounting for the inspection of the contact between the diamond and the drill point; and

Fig. 14 is a side view of the mounting shown in Fig. 13.

In accordance with the invention and as shown diagrammatically in Fig. 8, the drill 1 may consist of a fine wire having a vertical axis and mounted in a drill spindle 2 which likewise has a vertical axis and is mounted to rotate about that axis. A work holder 3 having a vertical longitudinal axis is positioned below the drill. This work holder may take the form of a rod. On the upper end of the rod 3 the diamond to be

drilled is held in what may be a conventional form of die mounting 5. In mounting the diamond in the die the diamond 4 is embedded in a matrix of relatively soft metal within a ring 6 and parts of the mounting are then ground away and provided with conical depressions 8 (note Fig. 6) so as to expose a predetermined point of the surface of the diamond to the action of the drill and to assist in confining the action of the drill to that point. Means are provided to impart a rapid up and down motion to the work holder and to subject the diamond to a series of rapidly recurring upward thrusts toward the drill 1 and in contact with the point thereof. The 10 conical depression in the die is provided with a suitable diamond cutting abrasive, e. g. diamond dust, and it is essentially the abrasive which effects the cutting action rather than the point of the drill, the latter serving to actuate the 15 cutting action of the abrasive. The rapid up and down movement of the work holder 3 not only brings the diamond into cutting relation with the point of the drill 1 but also withdraws the diamond away from that point and permits the abrasive to enter the depression or hole made by the drill so that the hole is always thereby replenished with the abrasive.

The vertical axis of the work holder during its movement is carefully and accurately controlled 20 in relation to the axis of the drill, so that the action of the drill is confined to the predetermined path through the diamond which it is desired to create and maintain.

In drilling extremely fine holes by means of 25 a fine wire, the action is preferably characterized by an infinite number of relatively gentle impacts of the diamond and abrasive against the point of the rotating drill, and the invention includes means for creating and maintaining these 30 relatively gentle contacts. However, in the use of an extremely fine wire serving as drill there is a tendency for the impact to bend the wire and therefore to cause distortion, and in accordance with the invention the excess energy of impact which tends to cause this distortion is absorbed by suitable means which will be illustrated.

The drilling unit includes the drill and its 35 mounting, the diamond holder or work holder and its mounting, and the apparatus associated with these elements. Any number of these units may be employed. Fig. 2 shows three. These units may be mounted upon an upright partition 40 supported on a platform 12.

The drill 1 is mounted at the lower end of a

vertical drill spindle 2 and may be secured in an orifice in the end of the spindle by any suitable means as, for example, a normally hard thermoplastic compound or by means of any other suitable cementing substance. The drill spindle is provided with ball bearings 15. The spindle and bearings are housed in a housing indicated generally by 17 and certain preferred features of the spindle mounting and lubrication thereof will be subsequently more fully described. Rotation of the spindle is effected by means of a pulley 20 driven by the belt 21 from a driving pulley 22 which in turn is driven by a belt 24 and pulley 25 fixed to the shaft 26 of a motor.

Referring now to the work holder 3 which holds the diamond and the movement of the work holder in relation to the drill, one way of securing the desired up and down movement of the work holder while maintaining the delicacy of cutting contact relation between the diamond and the drill is to suspend the work holder below and in spaced relation to the drill by means of a strand 30 (note Fig. 8) and to apply and maintain on this strand a predetermined tension urging the work holder upwardly and to bring the diamond on the work holder into cutting relation with the rotating point of the drill. Then by imparting a series of rapidly recurring downwardly directed impulses or displacements to the work holder the latter is given an up and down movement, the upward movement being controlled by the tension on the strand 30.

In order to properly confine or define the up and down movement of the work holder so that the longitudinal and vertical axes thereof will be properly maintained in a predetermined position in relation to the axis of the drill, the work holder is guided by suitable bearings and bearing mountings which may be provided with suitable lateral adjusting means so that the position of the vertical axis of the work holder can be adjusted in relation to the axis of the drill, with great accuracy.

Referring now to certain details of construction shown in the drawings for purposes of illustrating the principles, the work holder 3 is suspended below the drill 1 by means of a strand 30 which at one end thereof is operatively secured to the work holder by means of the hook 32. The other end of the strand passes over a pulley 33 supported on the upright partition 11 and terminates in a bucket or container 35 which may be weighted to a desired degree, as for example by means of shot 36. The strand is inclined as shown and thereby not only serves to provide a vertical biasing support for the work holder but also to maintain lateral pressure or bias of the work holder against the rollers 38 serving as guide rollers or bearings for the work holder. The bucket and shot constitute, therefore, a counter weight which provides the desired delicate upward urge or bias of the work holder to bring the diamond thereon into cutting relation with the drill, and a desired predetermined tension on the strand may be maintained by controlling the mass of the counter weight. Other equivalent means of providing and maintaining the desired upwardly and laterally urging force or bias to the work holder may be employed, the one specifically shown having been proved to be effective for the purpose.

Referring again to Fig. 8, it will be seen that the lever arm indicated generally at 40 and piv-

oted on the pivot 41 is rocked by means of the eccentric 42 mounted on shaft 43 and provides means for imparting to the work holder a rapid series of downwardly directed thrusts or displacements by contact of the arm 45 with the stop 46 on the work holder 3 which is normally biased upwardly against said arm 45. Following each downward thrust, the said arm 45 of course moves upwardly and releases the work holder, whereupon the tension on the strand 30 urges the work holder upwardly and brings the diamond at the top of the work holder into cutting relation with the rotating point of the drill. This upward urge results in an upward impact of the diamond and cutting abrasive against the point of the drill and tends to produce a certain amount of shock which tends to bend the drill (when the latter consists of a fine wire) and thereby to cause distortion. In order to prevent such distortion the excess energy of this impact, which is the cause of the distortion, may be absorbed by providing suitable shock absorbing means. One of such means may be provided by equipping the rod supporting strand with a resilient member, as a tension spring 48 which imparts resilient qualities to the strand so that the resiliency thus provided will absorb the shock and prevent the bending or distortion mentioned.

Referring more in detail to the means for imparting a series of rapidly recurring downward thrusts to the work holder, this, as already indicated, may take the form of a lever arm 40. One form of such arm is illustrated in Figs. 1, 2, 3 and 8, and this together with its associated mechanism will now be described in detail. This arm comprises an elongated lever bar provided intermediate the ends thereof and nearer one end than the other with a pivot 41. At the end of the short arm portion of said lever 40 there is provided a right angled bracket 50, including the arm 45 secured to the lever by means of screw 51 and positioned thereon with the aid of a flat spring 52 secured to the short lever arm by screw 53. The other end of the lever arm is given an up and down movement by means of an eccentric 42 mounted on a shaft 43 driven by a pulley 55 which in turn is driven by a belt 56 from a pulley 57 on the shaft 58. The pivot 41 is pivoted in a housing 60 having therein a hole 61 through which the lever arm extends. This housing is supported from a bracket 62 by means of a threaded member 64 which passes vertically through the housing in spaced relation to the lever arm 40 and terminates at one end in the adjusting knob 65 and at the other end is provided with a lock nut 66. In addition to this threaded member 64 a dowel pin 68 extends through the bracket 62 and housing 61 to assist in guiding said housing in its movement. The housing 60 is therefore vertically adjustable.

The reason for this is to permit raising of the work holder in relation to the point of the drill as the drilling operation progresses so as to permit the drill to penetrate the diamond to the desired extent.

Since the drill is fixed and does not move vertically it is necessary to move the diamond upwardly in order to effect the desired penetration of the drill. Since in the form shown in Fig. 3 the upward movement of the work holder is limited by the arm 45 which acts as a stop, raising of the pivot 41 will raise the upwardly limited position of the arm 45 and therefore permit the strand 30 to raise the work holder to a corresponding degree.

An alternative means of providing the desired

rapidly recurring downward thrusts on the work holder is illustrated in Figs. 10, 11 and 12. Here instead of rocking in a vertical plane, the levers 40 rock in a horizontal plane and this horizontal motion is converted into vertical downward thrusts in a manner which will be shown.

Referring to Figs. 10, 11 and 12, there is shown in Fig. 11 a group of two units including the horizontal levers 40, it being understood that any number of units may be employed. Referring to Fig. 11, the levers 40 are pivoted in the housing 60 by means of vertically aligned pivots 70 (corresponding to the horizontally aligned pivots 41 shown in Fig. 8), the said levers 40 being pivoted intermediate the ends thereof and nearer one end than the other. To the shaft 43 there is secured a collar 71 and an eccentric 72. Cooperating with this eccentric there is a bevelled T-shaped link member 73 mounted on the pivot 74. The strand 75 is provided with spring 76 and is secured to bracket 81 by means of anchor 81a. The strand 75 is also secured to levers 40 by means of pins 75a. The spring 76 and strand 75 biases the levers 40 against the link 73 so that when the eccentric 72 rotates, the combined action of the spring 76 and rockably mounted link 73 gives the levers 40 a rocking action in a horizontal plane. This rocking motion is, of course, communicated to the short arms 77 of the levers 40 which are provided with off-set bars 78 and a threaded contact member 79 which extends through said bars and bears against lever springs 80 secured at one end to the bracket 82 carried by the upright partition 11 and provided at the other end with a shoe 83 which may be made of any relatively soft material as, for example, leather, rubber or the like. As the short ends 78 of the levers 40 rock, the spring 80 on each of the levers which may be normally slightly arcuate as shown is flexed or flattened out and thus imparts a downward impulse to the work holder 3, thus performing a function analogous to that performed by the vertically rocking lever 40 illustrated in Fig. 8.

Referring now to the work holder mounting and the means for maintaining the vertical axis of the work holder in an adjustably predetermined position, during its movement, in relation to the axis of the drill, reference may be had to Figs. 1, 2, 3, 4, 9, 10 and 11. The structure illustrated (note particularly Fig. 4) includes a pair of vertically aligned and spaced guide rollers 38. As specifically illustrated, each member of the pair consists of two discs 85 in spaced relation rotatably mounted between needle points 88 which extend through holes in the yoke 90 and are fixedly positioned therein by means of set screws 91. The yoke 90 is supported by a bracket 92 secured to the front upright wall 11. The internal spacing of the discs 85 in relation to each other is such that the work holder rod 3 rides on the peripheral edges of the discs 85. A horizontal threaded member 94 extends through the yoke 90 intermediate the rollers and bears against the surface of the upright wall at one end, the other end of the threaded member terminating in a screw head 95. This threaded member therefore provides lateral adjustment of the yoke 90 and rollers 38 in one direction. Adjustment in another lateral direction perpendicular to the first mentioned direction is provided by an internally threaded bushing 98 which engages the threaded member 99, as shown more clearly in Fig. 9. The threaded member is engaged in a threaded socket in the yoke 90, and it will be clear that turning the adjusting nut 100 on the

threaded bushing 98 provides for lateral movement of the yoke 90 carrying the rollers 38 in the direction of the axis of the threaded member 99. Therefore the two threaded members 94 and 99, the axes of which are at right angles to each other, provide for lateral adjustment of the yoke 90 in different directions and therefore enable an accurate control over the position of the axis of the work holder 3 in relation to the axis of the drill 1. Set screws 102 maintain the yoke 90 in its adjusted position.

Now referring back to the spindle mounting and housing therefor, as previously stated, the spindle is provided with upper and lower ball bearings 15. These ball bearings are mounted in upper and lower housings 104 connected by an oil conduit 105 terminating at each end in threaded portions 106 engaging corresponding threaded portions in the housings 104. From the bottom of the lower housing 104 another conduit 108 leads to an oil collector 109 which may be an oil filter. The upper portion of the upper housing 104 communicates with an oil reservoir 110. The lower end of the spindle 2 carries a collar 112, the upper end of the collar being flanged and acting as an oil deflector.

A similar oil deflector 114 is provided in the upper housing. The oil reservoir 110 is secured to the upper housing by means of a threaded nipple 115 engaging a corresponding socket in the housing. By means of the construction shown, oil may be continuously passed in contact with the bearings and filtered and then re-used. The upper and lower bearing housings 104 are separated by a cylindrical shell 116 having an opening in the front thereof for the passage of the driving belt. The upper part of the cylindrical shell 116 carries threaded members 118 and 118a, one of which is provided with a threaded shank 119 having a knob 120 at the end thereof and a brake shoe 122 at the other end secured to the threaded shank 119 by means of a screw 123. The other threaded member 118a is provided on the inside thereof with a smooth bore through which extends a pin 124 likewise carrying a brake shoe 122a secured to the end of the pin 124 by means of a screw 125. The pin is normally held out of engagement with the pulley by means of a spring 121. Each of the brake shoes may be brought to bear against the driven pulley to control the speed thereof and the pin 124 with the brake shoe 122a at the end may be employed as a brake to stop the rotation of the spindle, if desired.

In order to observe the drilling operation a magnifying device is desirable, one form of which is shown in Figs. 13 and 14, comprising a microscope barrel 128 supported in bracket 129 by means of the screw 130, the bracket 129 being supported upon a rod 131 which in turn is supported in a socket 132 at the top of an adjusting screw 133 provided with a knob 135. The top of the bracket is provided with a member 136 carrying depending bars 137 secured therein by means of set-screws 138.

The magnifying unit thus described can be transferred from one drilling unit to the other to observe the drilling operation. For this purpose on each drilling unit there may be provided, as illustrated at the upper right hand corner of Fig. 11 and in Fig. 13, an adjusting and supporting member for the magnifying device. This adjusting and supporting member may comprise a bar 140 adjustably supported in relation to the 75 housing 104 by means of adjusting screws 141.

The bar 140 is provided with holes 142 for receiving the bars 137 on the bracket 129. The vertical position of the magnifying device can be adjusted by means of the adjusting screw 133.

What is claimed is:

1. Apparatus for drilling a hole in a diamond, or the like, comprising, in combination with a drill mounted to rotate about a vertical axis, a rod positioned below said drill and in vertical co-axial alignment therewith and having a work holder adapted to carry a diamond at the upper end thereof and in spaced relation to said drill; a pair of vertically spaced guide rollers; a flexible resilient strand; a pulley; one end of said strand being operatively secured to the rod intermediate the ends thereof and intermediate the said guide rollers, the other end of the strand being looped over said pulley and carrying a counter weight, said strand and counter weight suspending said rod below and in spaced relation to said drill and in yielding contact with said guide rollers and biasing said work holder upwardly to bring said diamond into cutting relation with the rotating point of said drill; means operatively connected with said rod and arranged and adapted to subject said rod to a series of rapidly recurring downwardly directed displacements in opposition to said upward bias, whereby a rapid up and down movement is imparted to the rod and the diamond is subjected to a series of rapidly recurring upwardly directed diamond cutting contacts with the point of said rotating drill.

2. Apparatus for drilling a hole in a diamond comprising, in combination with a drill mounted to rotate about a vertical axis, a rod positioned below said drill and having a work holder adapted to carry a diamond in spaced relation to said drill; counterbalanced suspension means suspending said rod in counterbalanced condition below and in spaced relation to said drill, and arranged and adapted to bias said rod upwardly and laterally; means operatively arranged in relation to said rod and adapted to subject said rod to a series of rapidly recurring downwardly directed displacements in opposition to said upward bias, whereby a rapid up and down movement is imparted to the rod; and guide means to determine the path of said up and down movement of the rod so that the axis thereof moves through a predetermined vertical path in relation to the axis of the drill, said guide means comprising a pair of vertically spaced guide rollers, each having vertically aligned parts positioned in rolling contact with and at one side of said rod in the direction of its lateral bias and thereby maintaining said rod in a predetermined vertical position in relation to the axis of the drill.

3. Apparatus for drilling a hole in a diamond comprising, in combination with a drill mounted to rotate about a vertical axis, a rod positioned below said drill and having a work holder adapted to carry a diamond in spaced relation to said drill; suspension means suspending said rod below and in spaced relation to said drill, and tending to bias said rod upwardly and laterally; means operatively arranged in relation to said rod and adapted to subject said rod to a series of rapidly recurring downwardly directed displacements in opposition to said upward bias, whereby a rapid up and down movement is imparted to the rod; and guide means to determine the path of said up and down movement of the rod so that the axis thereof moves through a predetermined vertical path in relation to the axis of the drill,

said guide means comprising a pair of vertically spaced guide rollers, each having vertically aligned peripheral parts positioned in rolling contact with and at one side of said rod in the direction of its lateral bias and thereby maintaining said rod in a predetermined vertical position in relation to the axis of the drill, said spaced guide rollers being mounted in a bracket and said bracket being provided with means for adjustment thereof in a horizontal plane toward and away from said rod.

4. Apparatus for drilling a hole in a diamond comprising, in combination with a drill mounted to rotate about a vertical axis, a rod positioned below said drill and having a work holder adapted to carry a diamond at the upper end thereof and in spaced relation to said drill; a resilient and flexible strand having one end operatively secured to said rod, counterweight means secured to the other end of the strand arranged and adapted to bias said rod axially upward and laterally; means operatively arranged in relation to said rod and adapted to subject said rod to a series of rapidly recurring downwardly and axially directed displacements in opposition to said upward bias whereby a rapid up and down movement is imparted to the rod and whereby the diamond is subjected to a series of rapidly recurring upwardly directed diamond cutting contacts with the point of said rotating drill, the resiliency of the strand absorbing shock resulting from said upwardly directed movements of the rod; and guide means arranged and adapted to laterally engage said rod to define the path of movement of the rod in a predetermined vertical path in relation to the axis of the drill.

5. Apparatus for drilling a hole in a diamond comprising, in combination with a drill mounted to rotate about a vertical axis, a rod positioned below said drill and having a work holder adapted to carry a diamond at the upper end thereof and in spaced relation to said drill; a flexible and extendable rod supporting strand having one end operatively secured to said rod, counter weight means secured to the other end of said strand to bias said rod axially upward and laterally; a pivotally mounted rocker arm; means to rock said arm at a predetermined rate; means at one end of said rocker arm and operatively connected to said rod to deliver a series of rapidly recurring downwardly and axially directed displacements to said rod in opposition to said upward bias, whereby a rapid up and down movement is imparted to the rod and the diamond is subjected to a series of rapidly recurring upwardly directed diamond cutting contacts with the point of said rotating drill; and guide means arranged and adapted to laterally engage said rod to define the path of movement of the rod in a predetermined vertical path in relation to the axis of the drill.

6. In apparatus for drilling a hole in a diamond or the like, wherein a drill carrying spindle is supported at a fixed operating level and a work holder and a vertically disposed work holder supporting rod are arranged beneath said spindle with said rod in vertical co-axial alignment therewith, the combination of vertically spaced guide rollers laterally engaging said rod at one side thereof, a pulley, a flexible strand having one end portion secured to said rod and the other end portion passing over said pulley, a counterweight secured to said other end portion of said strand and arranged and adapted to substantially counterbalance the weight of said rod and work

holder and to bias the same upwardly, and a tension spring interposed in said strand between said pulley and the rod, said pulley, said strand, said counterweight and said spring being positioned at one side of said rod and arranged and adapted to bias said rod laterally toward said guide rollers.

7. In apparatus for drilling a hole in a diamond or the like, wherein a drill carrying spindle is supported at a fixed operating level and a work holder and a vertically disposed work holder supporting rod are arranged beneath said spindle with said rod in vertical co-axial alignment therewith, the combination of vertically spaced guide rollers laterally engaging said rod at one side thereof, a pulley, a flexible strand having one end portion secured to said rod and the other end portion passing over said pulley, a counterweight secured to said other end portion of said strand and arranged and adapted to substantially counterbalance the weight of said rod and work holder and to bias the same upwardly, a tension spring interposed in said strand between said pulley and the rod, said pulley, said strand, said counterweight and said spring being positioned at one side of said rod and arranged and adapted to bias said rod laterally toward said guide rollers, a stop extending laterally from said rod, an oscillating arm having an end portion normally positioned to engage and limit the extent of upward movement of said stop, and means operatively connected to said arm and arranged and adapted to rapidly actuate said arm and thereby impart rapid vertical oscillation to said stop and said rod.

8. Apparatus for use in drilling fine wire dies comprising in combination, a die holder, means supporting the die holder for movement in a drilling axis to and from a drilling position, a counterweight connected to the die holder and support and arranged to give slight bias of the die holder toward drilling position, means to impart to the counterweighted die holder recurring impulses to move the die holder repeatedly away from drilling position, and means in addition to the counterweight acting on the die holder to absorb and dampen said repeated movement.

9. Apparatus for use in drilling fine wire dies comprising in combination, a die holder, means supporting the die holder for movement in a drilling axis to and from a drilling position, a counterbalance comprising the die holder and support and comprising a counterweight movable as a whole and arranged to bias the die holder and support toward drilling position, means to impart to the counterbalance recurring impulses to move the die holder repeatedly away from drilling position, and means in addition to the counterweight acting on the die holder to absorb and dampen said repeated movement.

10. Apparatus for use in drilling fine wire dies comprising in combination, a die holder, means supporting the die holder for movement in a drilling axis to and from a drilling position, the die holder being arranged for repeated movement away from drilling position under recurring im-

6 pulses, a counterweight adapted to give slight bias of the die holder toward drilling position, connecting means between the counterweight and the die holder comprising resilient means to absorb and dampen said repeated movement of the die holder under recurring impulses.

11. Apparatus for use in drilling fine wire dies comprising in combination, a die holder, means supporting the die holder for movement in a drilling axis to and from a drilling position, the die holder being arranged for repeated movement away from drilling position under recurring impulses, a counterweight adapted to give slight bias of the die holder toward drilling position, connecting means between the counterweight and the die holder comprising yielding means to absorb and dampen said repeated movement of the die holder under recurring impulses.

12. Apparatus for use in drilling fine wire dies comprising in combination, a die holder, means supporting the die holder for movement in a drilling axis to and from a drilling position, the die holder being arranged for repeated movement under recurring impulses away from drilling position, a counterweight adapted to give slight bias of the die holder toward drilling position, connecting means between the counterweight and the die holder comprising a flexible strand and spring to absorb and dampen said repeated movement of the die holder under recurring impulses.

13. Apparatus for use in drilling fine wire die comprising in combination, a die holder, means supporting the die holder for movement in a drilling axis to and from a drilling position, the die holder being arranged for repeated movement under recurring impulses away from drilling position, a counterweight adapted to bias the die holder toward drilling position, connecting means between the counterweight and the die holder comprising a flexible strand, the strand being mounted over a pivot, the connecting means also comprising a tension spring to absorb and dampen said repeated movement of the die holder under recurring impulses.

14. Apparatus for use in drilling fine wire dies, comprising in combination a die holder, means supporting the die holder for movement in a drilling axis to and from a drilling position, the die holder being arranged for repeated movement under recurring impulses away from drilling position, means for imposing a substantially constant counterbalancing force on the die holder and resilient means lesser in degree than the counterbalancing force between the die holder and the counterbalancing means to absorb and dampen said repeated movement of the die holder under recurring impulses, and means to impose said recurring impulses on the die holder between the die holder and the counterbalancing means, whereby the counterbalancing means remains in substantially constant position during said repeated movement of the die holder.
